US00D814516S

(12) United States Design Patent (10) Patent No.: US D814,516 S
(45) Date of Patent: * Apr. 3, 2018

(54) DISPLAY SCREEN WITH ICON

(71) Applicant: ROCKWELL AUTOMATION TECHNOLOGIES, INC., Mayfield Heights, OH (US)

(72) Inventors: Benjamin Henderson, Chardon, OH (US); Matthew R. Ericsson, Lyndhurst, OH (US); Ashish Anand, Mayfield Heights, OH (US)

(73) Assignee: Rockwell Automation Technologies, Inc., Mayfield Heights, OH (US)

() Term: 15 Years

(21) Appl. No.: 29/579,184

(22) Filed: Sep. 28, 2016

Related U.S. Application Data

(62) Division of application No. 29/512,460, filed on Dec. 18, 2014, now abandoned.

(51) LOC (11) Cl. 14-04

(52) U.S. Cl.

USPC D14/492

(58) Field of Classification Search

USPC D14/485-495

CPC G06F 3/0481; G06F 3/04817

See application file for complete search history.

Primary Examiner — Kevin Rudzinski

Assistant Examiner — Kathleen Jones

(57) CLAIM

The ornamental design for a display screen with icon, as shown and described.

DESCRIPTION

The sole FIGURE is a front view of a display screen with icon showing the new design.

The broken lines represent a display screen and form no part of the claimed design.

1 Claim, 1 Drawing Sheet
